Filed Mar. 12, 1962, Ser. No. 69,212

Term of patent 14 years

(Cl. D33—14)

Fig. 2

FIGURE 1 is a side elevational view of a furniture leg showing my design.

FIGURE 2 is a top view thereof, and

FIGURE 3 is an end elevational view thereof.

The inner face of the leg is unornamented.

The present design is characterized by a forked one piece leg having a flat inner surface merging with a reduced flat outer surface by means of a bevel, said forked portion tapering downwardly towards the lower ends and shaped as shown.

I claim:

The ornamental design for a furniture leg, as shown and described.
